HUMIDIFYING APPARATUS

Harry L. Husson, Westfield, N. J., assignor to
 Western Electric Company, Incorporated, New
 York, N. Y., a corporation of New York

Application February 27, 1934, Serial No. 713,115

4 Claims. (Cl. 257—182)

This invention relates to humidifying apparatus and more particularly to an apparatus to be used in connection with heating systems to humidify the air in buildings.

5 An object of the invention is to provide an apparatus of the kind described which shall be simple, efficient, automatic in operation, and self responsive to changes either in the amount of water evaporated thereby or in the relative 10 humidity of the air affected thereby.

With this and other objects in view one embodiment of the invention contemplates an assembly of a plurality of horizontally disposed combination heating and evaporating sections 15 having internal chambers fed with heating fluid, steam, hot water or the like, in customary fashion, and having open external evaporating pockets or troughs in cascade relation and heated by conduction from the heating chambers. 20 These evaporating pockets are supplied with water from the customary water supply of the building. Means are provided to regulate the supply of water to the evaporating troughs in accordance with the rate of evaporative consumption, comprising a float in one of the 25 troughs acting through an electrical circuit including a mercury switch and a solenoid to open and close the water supply valve. Means may further be provided such as a humidostat connected in the same circuit to effect control of the water supply in accordance with the amount of moisture contained in the air.

Other objects and features of the invention will appear from the following detailed description of one embodiment thereof taken in connection with the accompanying drawing in which the same reference numerals are supplied to identical parts in the several figures and in which

40 Fig. 1 is a partly diagrammatic broken view in front elevation of an air heating and humidifying apparatus embodying the invention;

Fig. 2 is a transverse vertical section thereof on the line 2—2 of Fig. 1;

45 Fig. 3 is a view in end elevation of the disconnected core of a modified form, and

Fig. 4 is a view thereof in front elevation.

In the embodiment of the invention herein disclosed, there are five horizontally disposed 50 combined heating and evaporating sections 10, of metal, arranged in a vertical stack and connected by and supported on interconnecting pipe sections 11 in well known fashion. The sections 10 have internal chambers, not shown, 55 to receive steam, hot water, or other heating

medium circulated therethrough from a feed pipe 12, having a control valve 13, and connecting to a boiler not shown. The pipe sections 11 serve to connect the internal chambers of the sections 10, as well as to support the sections 10 in spaced relationship to permit air to circulate freely around them. Each section 10 is formed in its upper part with a longitudinal trough 14 for the reception of water to be evaporated therefrom by heat conducted through the metal 10 walls of the section from the chamber within. One end of each trough floor is pierced by an 15 overflow pipe 15 which delivers excess water from each upper trough to the next below. These overflow pipes are located at alternate 15 ends of successive troughs so that the water flows the whole length of any intermediate trough before being delivered to the next below. The overflow pipe 15 of the lowest trough is connected to a drain pipe in the building system. 20 The entire stack is supported on the floor of the building by legs 21 attached to the lowest section 10 and provided with means such as the screws 22 whereby to adjust the stack to a level 25 position.

A vertical supply pipe 16 is located beside the stack of sections 10 and has a supply nozzle 17 for each of the three upper sections 10, adapted to deliver water into the corresponding trough 14. The pipe 16 is connected to the customary 30 water supply 23 of the building through a reducing valve 18 and a supply valve 19 operated to open and close by a solenoid 20. Each nozzle 17 is provided with a removable closure cap 30.

The lowest section 10 is formed at the outlet 35 end of its trough 14 with a well or pocket 24 in which is located a float 25. Adjacent the pocket is a post 26 on the top of which is pivoted a horizontal lever 21. One end of the lever is pivotally attached underneath to the float 25 40 and the other end of the lever carries a counterpoise 28. A mercury switch 29 is positioned on top of the lever to tilt therewith. The counterpoise 28 may be threaded on the lever to permit 45 of adjustment longitudinally thereon.

A connection box 31 is provided in any convenient location and is connected by wires 32 and 33 to the customary electric current supply wires 34 and 35 of the building. Wires 36 and 50 37 lead from the box to the terminals of the mercury switch 29. Wire 36 is connected through the box to wire 32 and supply wire 34. Wire 37 may be connected through the box to a wire 38 leading to one terminal of a humidostat 55

40, from whose other terminal a wire 39 leads back to the box and is connected therethrough to a wire 41 leading to one terminal of the solenoid 20. From the other terminal of the solenoid, another wire 42 leads back to the box and is connected to the wire 33 and the supply wire 35. Thus the mercury switch 29, humidostat 40 and solenoid 20 are connected in series across the supply wires 34 and 35.

- 10 The construction and mechanics of operation of the switch, humidostat and solenoid are not described or disclosed as these are standard and well known pieces of electrical apparatus whose nature, construction and individual function are well known in commerce and manufacturing, and are furthermore not relevant to the present invention. Suffice to say that a mercury switch such as 29 will close or open a circuit through its terminals upon being tilted in one direction or the other, a humidostat will close or open a circuit through its terminals when exposed to air having more or less than a predeterminedly variable degree of relative humidity, and a solenoid such as 20 will operate to actuate any mechanism operable by a push or a pull such as the valve 19 upon the flowing of an electric current through the solenoid.

The stack of sections 10 and its immediately associated parts may be preferably concealed within an ornamental housing 42 comprising sheet metal walls 43 and a cover 44. One or more of the walls 43 is provided with a grille or other ornamental opening 45. The top edges of the walls 43 are bent inwardly sharply down and then up to form a peripheral trough 46. The cover 44 has a flat top, short vertical side walls and a slightly sloping inner rim terminating inwardly in a downwardly extending vertical peripheral lip 47 adapted to be received in the trough 46. A short drain pipe 48 affixed in the trough 46 leads from the trough 46 to the trough 14 of the top section 10.

In the alternative form of core or stack shown in Figs. 3 and 4, the external stand pipe 16 is replaced by a supply pipe 49 extending up through the center of the stack and provided with supply apertures 50 closeable with plugs 51 homologous to the supply nozzles 17 and caps 30 of Figs. 1 and 2.

50 In operation, with cold weather outside the building, the valve 13 is opened and the interior chambers of the sections 10 are filled with steam, hot water, or the like. The wires 32 and 33 are connected to the supply wires 34 and 35. The well 24 is empty and the switch 29 in consequence tilted down to the right and closed. As the air in the room warms by convection around the sections 10, its relative humidity falls until it reaches the percentage for 55 which the humidostat 40 is set. The latter operates to close the circuit also and now current flows through the solenoid 20 to open the valve 19. Water then passes from the supply 60 23 through valves 19 and 18 and stand pipe 16 to the lowest uncapped nozzle 17 and thence into the trough 14 of the corresponding section 10. The water rises in the trough until it pours into the top of the overflow pipe 15 and down into the next lower trough, and so on until the water fills the well 24, raises the float 25 and finally operates the mercury switch to break the circuit. Immediately the solenoid 20 closes the valve 19 and stops the flow of water.

The water in the troughs 14 is heated and evaporates rapidly into the air which is heated and convected by the hot sections 10. If the supply of water becomes too low before the total volume of air is sufficiently moistened, the float will sink low enough to operate the switch as before to refill the troughs. But if the air is already sufficiently moist, closure of the circuit at the switch will be ineffective to operate the solenoid, for the humidostat holds the circuit open so long as the air is sufficiently moist. On the other hand, if the troughs 14 are all full of water and the air is not yet sufficiently moist the humidostat will keep the circuit closed at its station, but the float 25 will keep the switch 20 open and so will hold the valve 19 closed to prevent waste of water. Failure of current in the mains 34 and 35 will also keep the valve 19 closed. If the valve 19 be held open by any accidental failure, the excess water will be simply wasted down the last overflow pipe 15 into the waste system of the building.

At times when the apparatus is working at full evaporative capacity, the water charged air coming up from the top section may be heavily loaded with water to give up moisture by condensation on the first solid object contacted. This will be the inner surfaces of the housing top 44. Such condensation will gather and flow down into the trough 46 and thence by way of the pipe 48 back into the evaporating troughs 14. To facilitate the run off of such condensate, a false top 52 may be put into the top 44 sloping down to enable the moisture to run down instead of gathering in hanging drops.

A somewhat simpler and less sensitive, although often sufficient arrangement may be made by omitting the humidostat and its wires and connecting wires 37 directly to wire 41 in the box 31, as by a short circuiting plug, or fuse, or the like.

The embodiments of the invention herein disclosed are illustrative merely and may be modified and departed from in many ways without departing from the spirit and scope of the invention as pointed out in and limited solely by the appended claims.

What is claimed is:

1. An air heating and humidifying apparatus comprising a plurality of relatively vertically arranged elements each having internal chambers to receive a heating fluid and having an open external trough to receive water, means to admit a heating medium to the internal chambers, means to supply water to one of the troughs including a valve, means to lead the water in cascade through the troughs, a float in one of the troughs, a mercury switch connected to the float to be operated thereby, and a solenoid in circuit with the switch to operate the water supply valve.

2. An air heating and humidifying apparatus comprising a plurality of relatively vertically arranged elements each having internal chambers to receive a heating fluid and having an open external trough to receive water, means to admit a heating medium to the internal chambers, means to supply water to one of the troughs including a valve, means to lead the water in cascade through the troughs, a float in one of the troughs, a mercury switch connected to the float to be operated thereby, a solenoid in circuit with the switch to operate the water supply valve, and a circuit making and breaking hu-

midostat connected in series with the switch densate and deliver the same to the moisture and the solenoid.

3. In an air humidifier, the combination with means to heat air and means to supply moisture thereto, of a housing therefor having means to return moisture condensed therein to the moisture supply means comprising a member within the top of the housing adapted to lead moisture condensed thereon to a wall of

10 the housing, and a trough to receive the con-

5 denses and deliver the same to the moisture supply means.

4. In an air treating apparatus, a housing therefor comprising substantially vertical walls having a peripheral trough at the top thereof, and a top having a downwardly extending lip 5 to be received within the trough whereby moisture condensed within the top may be conducted into the trough.
